US0D1006119S

(12) United States Design Patent (10) Patent No.: US D1,006,119 S
(45) Date of Patent: * Nov. 28, 2023

(54) GAMING MACHINE

(71) Applicant: Aristocrat Technologies Australia Pty Limited, North Ryde (AU)

(72) Inventor: Timothy Seckel, Streamwood, IL (US)

(73) Assignee: ARISTOCRAT TECHNOLOGIES AUSTRALIA PTY LIMITED, North Ryde (AU)

() Term: 15 Years

(21) Appl. No.: 29/700,719

(22) Filed: Aug. 5, 2019

(51) LOC (14) Cl. 21-01

(52) U.S. Cl.

USPC D21/369

(58) Field of Classification Search

USPC D21/369, 370, 371

CPC .. G07F 17/32; G07F 17/3216; G07F 17/3213;

G07F 17/3202

See application file for complete search history.

(74) Attorney, Agent, or Firm — McAndrews Held & Malloy, Ltd.

(57) CLAIM

The ornamental design for a gaming machine, as shown and described.

DESCRIPTION

FIG. 1 is a front perspective view of a gaming machine showing my new design;

FIG. 2 is a front elevation view thereof;

FIG. 3 is a right side elevation view thereof;

FIG. 4 is a left side elevation view thereof; and,

FIG. 5 is a top plan view thereof.

The dashed broken lines in the drawings illustrate portions of the gaming machine that form no part of the claimed design.

Views of the gaming machine not shown form no part of the claimed design.

1 Claim, 4 Drawing Sheets
